RECIPROCATING PUMP

Camille Clare Sprankling Le Clair, Acton, London,
EnglandApplication August 11, 1943, Serial No. 498,169
In Great Britain August 24, 1942

7 Claims. (Cl. 103—154)

This invention relates to reciprocating pumps for pumping fluids.

For certain purposes, such, for example, as for pumping the de-icing liquid to de-icing apparatus on aircraft, it is necessary to provide a pump which can operate at a high speed and yet deliver an extremely small volume of liquid at each pumping stroke. The manufacture and operation of such a pump, designed on ordinary lines, is difficult, owing to the small dimensions which the different parts necessarily assume.

One object of this invention, therefore, is to provide a pump which, while capable of running at a very high speed and yet having an extremely small pumping capacity, is constructed from parts sufficiently large that they can be made by ordinary engineering methods as opposed to, say, watchmaking.

Expressed otherwise, an object of the invention is to reduce the output capacity of a pump of the smallest feasible dimensions to a fraction of what it would normally be.

According to the present invention, therefore, I provide a reciprocating pump, wherein the pumping operations are carried out by means of a plunger, which is slidable in a cylinder and is adapted to leave a clearance space in one end of the cylinder at the end of its instroke, characterised by the feature that it comprises a piston, hereinafter referred to as a "differential piston" which is movable in the said clearance space and is of less diameter than the cylinder, so that an annular space is left between the piston and the cylinder. The discharge capacity of the pump is the cross sectional area of this annular space multiplied by the effective stroke (as defined hereinafter) and since the area of the annulus is less than the whole area of the cylinder of which it is a part, it is obvious that the discharge of the pump is reduced by this principle. Further, by varying the diameter of the piston the amount of reduction of the discharge can be varied, since the larger the piston the smaller the annulus (and the output capacity) and vice versa.

In one constructional form, the pump comprises a cylinder provided with inlet and outlet ports, a plunger which is slidable in the cylinder and controls the opening and closing of the inlet and outlet ports, the motion of the plunger being such as to leave a clearance space at one end of the cylinder at the end of the instroke, or suction stroke, of the plunger, at least one transfer passage connecting the said inlet and outlet ports, and a piston, of smaller diameter than the plunger, which is reciprocable in the said clearance space and is adapted to be moved both independently of the plunger and also in company therewith. The arrangement is such that the discharge of liquid from the cylinder is car-

ried out principally by the movement of the piston in the said clearance space, this taking place mostly while the plunger and piston are moving towards each other but also, in some circumstances, while they are in contact and moving in the same direction.

For the purpose of description the discharge stroke may thus be said to be divided into three parts. During the first part, up to the closing of the inlet port, the plunger and piston move together in contact in the same direction and at the same speed. Any liquid displaced by the difference in area between the plunger and the piston is discharged through the inlet port back to suction.

During the second or effective part of the stroke, from the closing of the inlet port to the opening of the outlet port a volume of liquid is entrapped; hence the piston is compelled to move forward still in the same direction, but at a greater speed than the plunger in order that its displacement may be equal to the displacement of the plunger and thereby leave the necessary volume for the entrapped liquid.

During the third part of the stroke, after the outlet port has opened, the liquid is discharged by virtue of spring pressure on the piston which now descends towards, and until it contacts with, the plunger. This may be before or after the completion of the discharge stroke, it being of little consequence which occurs, but it is desirable that it shall occur before the outlet port closes on the return stroke of the plunger because otherwise the volumetric efficiency of the pump will be impaired.

After the outlet port closes, the plunger and piston descend in contact with each other and as the plunger is of larger diameter than the piston a void is caused in the cylinder, which void is filled by the incoming liquid immediately the inlet port is opened by the plunger towards the end of the return stroke.

In a preferred constructional form of the invention, the plunger controls the opening and closing of an inlet port communicating with a source of supply of the liquid, and also the opening and closing of an outlet port, both ports being connected by a passage or channel in the cylinder wall to a part of the cylinder isolated from the ports by the plunger.

A piston, which is of less diameter than the cylinder, is movable in the said part of the cylinder and is normally spring-pressed into contact with the plunger. Thus, when the plunger is carrying out its discharge stroke and has closed the inlet port, liquid is trapped in the cylinder space in which the piston is movable and, as the liquid in the said space is displaced by the plunger, the piston is forced outwards against the pressure of the spring. During the con-

tinued movement of the plunger in the same direction, the outlet port is opened and the cylinder space in which the piston is movable is connected to the pump outlet. In these circumstances, the piston returns rapidly under the action of its spring until it is again in contact with the plunger, at the same time displacing liquid from the cylinder. On the return stroke when the inlet port is again opened by the plunger liquid is sucked into the cylinder space around the piston to replace that discharged on the previous stroke.

One constructional form of the invention, applied to a pump for pumping the de-icing liquid to de-icing apparatus on aircraft, is hereinafter described, by way of example, with reference to the accompanying drawings, whereon—

Fig. 1 is a sectional elevation of the pump; and

Fig. 2 is a sectional view of a multiple pumping unit comprising a number of reciprocating pumps according to the invention.

In the following description, reference is made to the "top" and "bottom" of the various parts of the pump. These expressions, however, are only used for the purpose of description, and it is to be understood that the pump axis can be arranged vertically or at any desired angle to the vertical.

The pump body comprises a hollow casing 1 which is fixed to a base 2 and is fitted with a cylinder 3 bored to receive a slideable plunger 4, the lower end of which projects below the cylinder and is preferably formed with an enlarged head 5. The top end of the cylinder is closed by a plug 6 seated on a joint member 7 at the top end of the cylinder and bored axially to provide a guide for a differential piston 8 of relatively small diameter (less than that of the cylinder bore) which is slideable in the guide. The top end of the piston projects out of the plug 6 and is fitted with an inverted cup washer 9 forming a support for the bottom end of a coil spring 10. A cap 11 is fitted onto the upper end of the said plug and is arranged to enclose the said washer and the coil spring, the upper end of the latter bearing against the inside of the top of the cap. The latter is formed with a hole 12 through which its interior communicates with the atmosphere. An apertured cover 13 is screwed upon the top end of the casing and encloses the above mentioned cap 11. The coil spring 10 acts to hold the bottom end of the piston normally in contact with the upper end of the plunger 4 (except during certain phases of the pumping cycle as explained later) and thus also to keep the headed end 5 of the plunger in contact with a cam 14 rotatably arranged in the base of the pump which is hollow and may act as a liquid reservoir.

At such times as the piston 8 and plunger 4 are not in contact, the plunger is kept in contact with the cam either by the hydraulic pressure generated by the spring 10 acting on the piston or (during the time the outlet port referred to hereinafter is open) by the discharge pressure against which the pump is delivering.

A longitudinal inlet passage 15, formed at the lower end of the cylinder, provides communication between the liquid-filled interior of the hollow base 2 and the cylinder bore through a transverse inlet port 16 formed in the cylinder wall. A continuation 16A of the inlet port formed at the diametrically opposite side of the cylinder

communicates with the lower end of a longitudinal channel 17 formed in the cylinder wall. The top end of the channel is connected by a transverse transfer port 18 to the cylinder bore above the plunger 4, in that part of the bore which the piston 8 occupies. A transverse outlet port 19 in the cylinder connects the pump outlet branch 20 to the cylinder bore, and a continuation 19A thereof, formed diametrically opposite the first mentioned part 19, communicates with the said longitudinal channel 17 at a point arranged between the inlet and transfer ports 16A and 18.

The plunger 4 is formed with an annular recess 21 which, when the plunger is in its lowermost position, is aligned with the said inlet ports 16 and 16A, so that liquid can be drawn by suction from the interior of the pump base 2 through the inlet passage 15, the ports 16 and 16A, the channel 17 in the cylinder and the transfer port 18 to fill the annular space 22 surrounding the piston above the plunger. The outlet ports 19 and 19A are masked by the part of the plunger above the said recess 21, so that no liquid can flow from the channel 17 into the pump outlet 20 or vice-versa. When the cam 14 is rotated, the plunger 4 and the piston 8 are both lifted against the opposing action of the coil spring 10. During this movement, the recess 21 in the plunger is moved upwards to cut off communication between the inlet passage 15 and the inlet port 16 and the channel 17. As the plunger continues to rise, the outlet ports 19 and 19A still being closed, there is no way of escape for the liquid and, consequently, the plunger area being greater than the piston area, the piston is forced upwards at greater speed than the plunger, against the action of the spring 10, which is compressed, and pressure is generated by the spring load on the piston. On the continued upward movement of the plunger, however, the said recess 21 eventually opens communication between the port 19A and the outlet port 19, thereby releasing the liquid entrapped in the passage 17, transfer port 18 and pump chamber 22 and permitting the piston 8 to be forced downwards rapidly by the coil spring 10. Liquid is thus discharged from the cylinder space above the plunger through the said channel 17 and the ports 19A and 19 into the pump outlet 20. The independent downward movement of the piston under the influence of its spring 10 is stopped by its contact with the plunger 4. This may take place before or after the latter has reached the top end of its stroke and thereafter as the cam 14 continues to rotate, the plunger and the piston descend in company.

When the recess 21 again commences to register with the inlet ports 16 and 16A, liquid is again sucked up from the hollow pump base 2 through the inlet passage 15, the ports 16 and 16A and the longitudinal channel 17 and into the cylinder space 22 above the plunger surrounding the piston 8 and replaces the liquid discharged during the previous stroke.

From the foregoing it will be understood that the volume of liquid discharged per stroke will be that represented by the difference between the plunger and piston areas, i. e., the area of the annulus multiplied by the stroke between the closing of the inlet ports 16 and 16A and opening of the outlet port 19.

The above is a description of one single pump. It will be appreciated, however, that two or more such pumps can be combined into one multiple pumping unit. If a number of pumps is used,

as shown in Fig. 2, they may be mounted upon a base 23 and arranged in any desired relationship to each other. For example, they may be arranged in single line or in V-form as in Fig. 2, or opposed or radially around the base. If arranged in line two or more such lines may be arranged parallel to each other on one base with two or more cam shafts to operate them. In this case, the pumps of one line may be staggered with relation to those of the adjacent line or lines.

When arranged in V, opposed or radial formation one cam 24 may operate more than one pump as shown in Fig. 2.

The constructional form of the invention shown in Fig. 2 comprises two banks of aligned pump units 25 arranged in V-form upon a hollow base 23, the interior 23a of which may be kept filled with the liquid to be pumped, the supply being either by gravity or under pressure. The interior 23a is connected to each pump suction by a port 23d. Alternatively, a separate duct 23b may be used, this duct being connected to the individual pump suctions by the ports 23c.

A single operating shaft 26 extends axially through the base and is provided with a number of axially-spaced cams 24, each of which serves to operate the plungers of two pump units. Each unit has a separate outlet 27 and an electric motor drives the operating shaft.

In this constructional form the inlet and outlet ports are led through the joint face between the pump body and the base. By adopting this principle the pipe connections are attached to the base and not to the individual pumps, so that it is possible to detach, remove and replace any pump without breaking pipe connections.

I claim:

1. A reciprocating pump, comprising a cylinder provided with an inlet port connected to a source of liquid and an outlet port, a plunger slidable in said cylinder and adapted to control the opening and closing of said inlet port and said outlet port, the extent of movement of said plunger being such that it leaves a space between its end and the end of said cylinder at the terminus of its instroke, a transfer passageway connecting said inlet port and said outlet port with said space, said transfer passageway being adapted to permit flow of liquid to said space when put in communication with said inlet port by said plunger and being adapted to permit flow of liquid from said space when put in communication with said outlet port by said plunger, a differential piston having a diameter smaller than the diameter of said plunger and reciprocable in said space in said cylinder, and resilient means acting on said differential piston, said differential piston being moved against said resilient means on the instroke of said plunger and being moved through a pumping stroke by said resilient means when said plunger opens said outlet port.

2. A reciprocating pump, comprising a cylinder provided with an inlet port connected to a source of liquid and an outlet port, a plunger slidable in said cylinder and adapted to control the opening and closing of said inlet port and said outlet port, the extent of movement of said plunger being such that it leaves a space between its end and the end of said cylinder at the terminus of its instroke, a transfer passageway connecting

said inlet port and said outlet port with said space, said transfer passageway being adapted to permit flow of liquid to said space when put in communication with said inlet port by said plunger and being adapted to permit flow of liquid from said space when put in communication with said outlet port by said plunger, a differential piston having a diameter smaller than the diameter of said plunger and reciprocable in said space in said cylinder, and resilient means biasing said differential piston into said space, said differential piston being moved against said resilient means on the instroke of said plunger and being moved through a pumping stroke by said resilient means when said plunger establishes communication through said outlet port.

3. A reciprocating pump as set forth in claim 1 wherein said plunger is provided with an annular groove which is adapted to register alternately with said inlet port and with said outlet port.

4. A reciprocating pump as set forth in claim 2 wherein said plunger is provided with an annular groove which is adapted to register alternately with said inlet port and with said outlet port.

5. A reciprocating pump as set forth in claim 2 wherein said plunger is provided with an annular groove which is adapted to register with said inlet port when said plunger is at the end of its outstroke and to register with said outlet port when said plunger is at the end of its instroke.

6. A reciprocating pump, comprising means forming a cylinder, a passageway across said means on both sides of said cylinder forming an inlet port in communication with an inlet passage, a second passageway across said means on both sides of said cylinder forming an outlet port in communication with an outlet passage, a plunger slidable in said cylinder having an annular groove formed therein alternately to establish communication through either said inlet port or said outlet port, the extent of movement of said plunger being such that it leaves a space between its end and the end of said cylinder at the terminus of its instroke, a transfer passageway connecting said inlet port and said outlet port with said space, said transfer passageway being adapted to permit flow of liquid to said space when put in communication with said inlet passage by said plunger and being adapted to permit flow of liquid from said space when put in communication with said outlet passage by said plunger, a differential piston having a diameter smaller than the diameter of said plunger and reciprocable in said space in said cylinder, and resilient means biasing said differential piston into said space, said differential piston being moved against said resilient means on the instroke of said plunger and being moved through a pumping stroke by said resilient means when said plunger establishes communication through said outlet port.

7. A reciprocating pump as set forth in claim 6 wherein said transfer passageway is formed in said cylinder forming means.

CAMILLE CLARE SPRANKLING LE CLAIR.
